(57) **CLAIM**

What is claimed is the ornamental design for a curling iron stand, as shown and described.

DESCRIPTION

FIG. 1 is a perspective view of a curling iron stand, showing the new design;

FIG. 2 is a cross-sectional view thereof, taken generally along lines 7-7 of FIG. 3;

FIG. 3 is a top plan view thereof;

FIG. 4 is a left-side elevational view thereof, the right-side elevational view being a mirror image thereof;

FIG. 5 is a bottom plan view thereof;

FIG. 6 is a front elevational view thereof; and,

FIG. 7 is a rear elevational view thereof.
